 Filed Oct. 2, 1964, Ser. No. 401,154
 3 Claims. (Cl. 116—124)

This invention relates to a device for retaining a visible indication of the particular setting of a control knob with respect to a dial. In particular, the invention relates to a device for indicating a previous setting of an electrical component operated by way of a control knob mounted coaxially with the device.

In operating electrical apparatus, it is frequently desirable to have some means for indicating the orientation to which a particular control knob has been set so that the knob can be rotated to a different position and brought back to the original orientation quite readily. In accordance with this invention, an annular ring is provided as part of such a device and is journaled upon the round shank of a nut that may also serve to hold the electrical component on a panel, the nut being threaded upon a journal that extends through an opening in the panel and through which, in turn, an adjusting shaft extends. The electrical component to which the adjusting shaft is attached may be any one or more of the tunable electrical components, such as capacitors, inductors, potentiometers, switches, and the like. A dial is provided on or in conjunction with the panel and the ring or knob has an indicator that may be set at any point on the dial. Friction means are provided to restrict the rotation of the ring so that it will not easily be moved out of place, although it can be rotated deliberately. A tuning knob, which may be of any type, is attached to the shaft and has a pointer that may be set with respect to the dial, but may also be set with respect to the indicator on the ring.

One of the principal objects of the present invention is to provide a device that will retain an indication of the setting of an adjusting knob of an adjustable electrical component. Further objects will be apparent from the following specification, together with the drawing in which:

FIG. 1 is a view partly in cross-section of a dial setting device according to the invention; and

FIG. 2 shows a front view of the dial setting device of FIG. 1.

The dial setting device in FIG. 1 is to be used in conjunction with a variable electrical component 11 which may be a volume control, tuning capacitor, a variable inductance, a switch, or any combination thereof fitted with a tuning or adjusting shaft 12 rotatable, either continuously or in steps, through some angle. Some of these components have typical maximum angles, such as 180 degrees for a tuning capacitor or 270 degrees for certain potentiometers or even more than 360 degrees for other potentiometers, and this invention may be used with any of them. The shaft 12 extends through an externally threaded journal 13 which is held within an aperture 14 in a panel 16 by the pressure between a regular hex-nut 17 and a special nut 18. The nut 17 is merely a spacer to determine the distance that the outer end of the journal 13 will extend beyond the panel 16, and it need not be used in every instance.

The nut 18 has a round shank 19 threaded on the journal 13 and tightened against the panel 16 so that pressure between the end of the shank 19 and one surface of the nut 17 holds the component 11 firmly in place. A lock washer may be used in the customary manner. In addition to the round shank portion 19, the nut 18 has a radially extending shoulder 21 at the other end. Preferably the entire axial length of the nut 18, including both

2

the shank portion 19 and the shoulder 21 be substantially equal to the face of the panel 17. This distance may be referred to at the effective length of the journal. The shoulder 21 is normally hexagonal.

5 Journaled on the round shank 19 is an annular ring 22 having a section 23 of reduced thickness immediately adjacent to the shank and with a central bore 20 large enough for unhindered rotation on the shank. The total axial length of the annular ring 22 at the periphery thereof is substantially equal to the axial length of the nut 18, but the section 23 must have a shorter axial dimension than the distance between the face of the panel 16 and the shoulder 21. Between the outer end of 10 23 and the near surface of the shoulder 21 is a frictional device, such as a compression spring washer 24, that bears against both the end of the section 23 and the shoulder 21 to restrict the freedom of rotation of the ring 22. The friction provided by the spring 24 must be sufficient to hold the ring 22 in whatever position it may be set, and yet the frictional force must not be sufficient to make it 15 unduly difficult to turn the ring to a new setting whenever it may be desired to do so.

Attached to the shaft 12, by a set screw 25, is an adjusting knob 26 which is shown as having a pointer 27, 20 although this pointer may actually be in the form of a colored dot or any other means for indicating the setting position of the knob and hence of the shaft 12.

In FIG. 2 there is a dial 28 on or attached to the surface of the panel 16 in the area around the ring 22. The 25 ring, itself, is provided with at least one indicator or marker 29 that can be set in conjunction with the dial 28. The knob 26 and its pointer 27 are also shown in FIG. 2.

In operation, the knob 26 may be set so that the pointer 30 27 is opposite any mark on the dial 28. If it is desired to move the knob to a different location and then to return it to the original location, the ring 22 may be rotated so that the indicator 29 is located in the same spot as the pointer 27. Thereafter, the knob 26 may be 35 moved to a different position and then brought back to the original position by realigning the pointer 27 with the indicator 29. Because of the fact that the knob 26 is spaced from the ring 22 and therefore exerts no drag 40 thereon, and further because of the fact that no other moving part of the entire apparatus is in contact with the ring 22, the setting of the indicator 29 can be expected to be relatively permanent until it is deliberately moved to a different position.

While this invention has been described in terms of 45 the specific embodiment, it will be understood by those skilled in the art that various modifications may be made therein without departing from the true scope of the invention as determined by the following claims.

What is claimed is:

50 1. A dial setting device for an adjustable electrical component comprising an adjusting shaft attached to said component, an externally threaded journal through which said shaft extends, and a panel having an aperture through which said journal extends, said device comprising: an internally threaded nut fitting on said externally threaded journal to hold said electrical component in place on said panel, said nut having a round shank, one end of which bears against said panel, and a shoulder extending substantially radially from the other end of said shank, the surface of said shoulder facing said one end of shank being distant from said one end by a predetermined length; an annular ring surrounding said shank to be freely rotatably journaled thereon, the thickness of the portion of said ring in contact with said shank being less than the length of said shank; a compression device between said ring and said nut to apply pressure and rotational friction therebetween; a dial on said panel; an indicator

on said annular ring settable with respect to said dial; and a knob on said shaft spaced from said ring and having means for indicating the setting of said knob with respect to said indicator.

2. A dial setting device for an adjustable electrical component comprising an adjusting shaft attached to said component, an externally threaded journal through which said journal extends, said device comprising: an internally threaded nut fitting on said externally threaded journal to hold said electrical component in place on said panel, said nut having a round shank, one end of which bears against said panel, and a shoulder extending substantially radially from the other end of said shank, the surface of said shoulder facing said one end of shank being distant from said one end by a predetermined length; an annular ring surrounding said shank to be freely rotatably journaled thereon, the thickness of the portion of said ring in contact with said shank being less than the length of said shank; a compression device on said shank in the region thereof between the face of said ring distal from said panel and the surface of said shoulder facing said panel to apply axial pressure and rotational friction therebetween; a dial on said panel; an indicator on said annular ring settable in conjunction with said dial; and a knob on said shaft spaced from said ring and having a pointer settable with respect to said indicator.

3. A dial setting device for an adjustable electrical component which comprises an adjusting shaft attached to said component, an externally threaded journal through which said shaft extends, and a panel having an aperture through which said journal extends, said device comprising an internally threaded nut fitting on said externally

threaded journal to hold said component on said panel, said nut having a round shank of predetermined length and a hexagonal shoulder extending substantially radially therefrom at one end; an annular ring surrounding said shank to be freely rotatably journaled thereon, the periphery of said ring having an axial length substantially equal to the axial length of said shank plus the axial length of said shoulder, and the portion of said ring radially closest to said shank having an axial length less than the axial length of said shank; a compression spring between said ring and said shoulder to exert frictional drag on said ring to restrict the freedom of rotation thereof, whereby said ring will remain in any set position; a dial on said panel; and indicator on said annular ring settable in conjunction with said dial to serve as a predetermined setting; and a knob on said shaft spaced from said ring and having a pointer indicating the setting of said knob with respect to said indicator.
